COLLATOR

Anthony V. von Haase, Cleveland, Ohio, assignor,
by mesne assignments, to American Type
Founders, Incorporated, Elizabeth, N. J., a cor-
poration of New Jersey

Application February 17, 1945, Serial No. 578,419

9 Claims. (Cl. 270—58)

1

This invention relates to collating apparatus of the kind used in collecting or assembling individual sheets in a desired order or sequence by feeding the sheets substantially simultaneously from a plurality of groups or bundles, and aims to provide improved and simplified apparatus of this character which will function in a positive and reliable manner and will be capable of highly satisfactory performance even when operated at a relatively rapid rate.

Another object of the present invention is to provide an improved construction for a collating apparatus of this character, in which novel ejectors are employed for feeding the sheets from the bundles.

Still another object of this invention is to provide improved collating apparatus of the character mentioned, in which novel actuating means involving the use of flexible strands is employed for actuating the ejectors.

Yet another object of the invention is to provide improved collating apparatus of this type, in which the flexible strands are tapes which extend in superposed relation around an oscillatable driving member.

A further object of this invention is to provide improved collating apparatus of this kind, having novel sheet guiding means for bringing the sheets into a relatively compact group and for facilitating the operation of grasping and removing such group of sheets from the apparatus.

This invention can be further briefly summarized as consisting in certain novel combinations and arrangements of parts hereinafter described and particularly set out in the appended claims.

In the accompanying sheets of drawings:

Fig. 1 is a perspective view of a collator embodying the present invention;

Fig. 2 is a partial front elevation further illustrating the paper guide or hood;

Fig. 3 is a side elevation of the apparatus with portions of the housing broken away;

Fig. 4 is a transverse sectional view taken through the apparatus substantially on line 4—4 of Fig. 3;

Fig. 5 is a partial side elevation on a larger scale, showing the guideway and portions of the actuating tape for one of the ejectors;

Fig. 6 is a sectional detail view taken transversely of one of the guideways as indicated by line 6—6 of Fig. 5;

Fig. 7 is a sectional elevation showing one of the ejectors on a larger scale, the view being taken substantially as indicated by line 7—7 of Fig. 4;

2

Fig. 8 is a sectional detail view taken through an ejector on line 8—8 of Fig. 7;

Fig. 9 is a partial plan view of one of the ejectors;

Fig. 10 is a partial plan view of a modified construction for the ejectors; and

Fig. 11 is a partial side elevation thereof.

The embodiment of the invention which is illustrated in the drawings will now be described in greater detail but, before proceeding with the detailed description thereof, it should be understood that the invention is not limited to the particular apparatus here illustrated but may be embodied in various other specific forms of collating apparatus.

The apparatus here shown includes a housing 10 having a base 11 provided with wheels or casters 12, and laterally spaced upright side and intermediate walls 13 and 14 extending above such base. The housing 10 also includes a curved or sloping bottom 16 which is located at varying distances above the base 11, and a plurality of spaced transverse partition walls 17 extending at substantially right angles to the curved or sloping bottom. The bottom 16 and the partition walls 17 cooperate with the side and intermediate walls 13 and 14 in defining two substantially parallel rows of bins or pockets 18 which are adapted to receive bundles 19 of the sheets which are to be fed and collated. The intermediate wall 14 can be omitted, if desired, in which case the housing contains only a single row of the bins 18.

As shown in Fig. 3 the partition walls 17 of the housing extend outwardly from the sloping bottom 16 in radiating or converging relation and the bins 18 are open at their outer ends for the insertion of the bundles 19 and the feeding of the individual sheets therefrom. The bins 18 are provided adjacent their inner or lower ends with suitable bundle supports or backing plates in the form of brackets 21 which are mounted on the partition walls 17 so as to be adjustable therewith to suit the size of the sheets and the positions in which the bundles are to be supported in the bins.

The open outer ends of the bins 18 cooperate with a section of the housing 10 which may be referred to as a hood or paper guide 22 and which will be described in greater detail hereinafter. For the present it is sufficient to point out that the hood 22 has a transversely extending slot or opening 23 through which the collated sheets are delivered in the form of a relatively compact group or bundle 24.

55 The feeding of the sheets from the bundles 19

is accomplished by means of ejectors 26, one of which is reciprocably movable in each of the bins 18. Each of the ejectors 26 comprises a bracket 27 which is carried by a transversely extending bar or actuating shaft 28 and a substantially U-shaped member 29 connected with the bracket. The bracket 27 is here shown as comprising a hub or collar 30 adapted to be secured on the shaft 28 as by means of the setscrew 31, and a forwardly extending plate-like body 32 welded or otherwise attached to the hub 30 and having diverging arms 32a which are provided at their free ends with locking recesses 33. The U-shaped member 29 has a transverse portion 29a pivotally mounted on the bracket 27 at a point adjacent the hub 30 and has forwardly extending substantially parallel arms 29b which are releasably engageable in the locking recesses 33 for a purpose to be presently explained. The pivotal connection can be formed as here shown by providing the transverse portion 29a with a yoke 34 at its midpoint which straddles the bracket portion 32 and is received in a recess 34a of the latter.

The outer ends of the arms 29b are provided with a sheet gripping or pushing members 35 which may be in the form of yoke-like brackets 36 welded or otherwise connected thereto and carrying sheet engaging rollers 37 formed of soft rubber or other suitable friction material. The rollers 37 are mounted in the brackets 36 by means of a shaft or pin 38 whose ends extend through slots 39 provided in the spaced arms or side walls 36a of the brackets. Just inwardly of the rollers 37 the brackets 36 are provided with substantially U-shaped locking members 40 which serve to prevent rotation of the rollers when the latter are pressed thereagainst during a forward or feeding stroke of the ejector. The outer ends of the spaced arms 29b of the U-shaped member 29 are spanned and connected by a yoke 41 having a lever or finger 42 extending forwardly therefrom at a point between the brackets 36 and the purpose of which will be presently explained.

The pivotal connection provided between the bracket 27 and the portion 29a of the U-shaped member 29 permits the latter to swing relative to the bracket from a sheet engaging position shown in full lines in Fig. 7 to a non-feeding or idle position which is shown in this same view in broken lines. While in the sheet feeding position, the pushers 35 of the U-shaped member 29 rest upon the uppermost sheet of the bundle 19 and are pressed thereagainst by the action of gravity. While the U-shaped member 29 is in this position the rollers 37 are in frictional engagement with the uppermost sheet, and when the ejector 26 is moved through a feeding stroke in a direction outwardly of the bin 18, the rollers 37 are shifted bodily to engage the U-shaped locking members 40 and are held or locked against rotation by the latter. This outward movement of the ejector causes the locked rollers 37 to push or slide the uppermost sheet off the bundle 19 and feed the same from the bin through the open outer end thereof. During the inward movement or return stroke of the ejector 26, the rollers 37 are shifted away from the U-shaped locking members 40 and are permitted to roll freely over the bundle 19 until the ejector reaches its innermost or fully retracted position.

As mentioned above, the U-shaped member 29 of the ejector 26 is movable to a non-feeding position in which it is adapted to be temporarily held by the locking recesses 33 of the bracket 27.

The movement of one or more of the ejectors to such a non-feeding position is desirable at times when the feeding of sheets from particular bins is not needed or desired. The movement of the U-shaped member 29 to its non-feeding position is easily accomplished by the operator grasping the forwardly extending lever 42 and lifting or swinging the U-shaped member 29 to engage the arms 29b thereof in the locking recesses 33.

A bowed spring 43 carried by the arms 29b, in spanning relation thereto, acts to releasably hold the arms in the locking recesses 33. As long as the arms 29b remain engaged in the locking recesses 33 the U-shaped member 29 will be held in its non-feeding position but when this member is to be returned to its feeding position, the operator simply grasps the lever 42 and disengages the arms from the locking recesses and permits the U-shaped member 29 to swing downwardly to its feeding position with the rollers 37 in engagement with the upper sheet of the bundle 19.

As mentioned above, the ejectors 26 are carried by the transversely extending bars or shafts 28. The desired reciprocating movement for the ejectors 26 can be imparted thereto by causing a translatory shifting of the shafts 28 in their respective bins or pairs of bins. To permit of this shifting of the shafts 28 the outer side walls 13 and the immediate wall 14 are provided with slots 45 which extend lengthwise of the bins 18 and through which the shafts extend. Channel-shaped members 46 mounted on the side walls 13 form guideways 47 which are substantially coextensive with the slots 45. The outer ends of the shafts 28 extend outwardly through the slots 45 into the guideways 47. Guide members or blocks 48 are carried by the outer ends of the shafts 28 and are slideable in the guideways 47. The guide members 48 are retained in seating engagement in the guideways by means of compression springs 49 which are disposed around the outwardly extending reduced portions 50 of the shafts 28.

To provide for substantially simultaneous feeding and retracting strokes of the shafts 28 and the ejectors 26 carried thereby, a relatively simple actuating means is provided for imparting pulling forces to the guide members 48 alternatively in opposite directions. This actuating means includes a pair of laterally spaced oscillatable pulleys or drums 52 which are mounted on a shaft 53 so as to be oscillatable about a common axis. A group of flexible strands 54 corresponding in number with the number of ejector shafts 28, extends over each of the pulleys 52. The strands of these groups have their ends connected with the outer ends of the ejector shafts by means of yokes 55 mounted on the reduced shaft portions 50. The yokes 55 are located outwardly of the compression springs 49 and are retained on the reduced shaft portions 50 by means of pins or cotter keys 56. Since the arrangement and operation of the groups of strands 54 is substantially the same for both sides of the machine, the detailed description from this point forward is simplified by referring to one group only.

The flexible strands 54 are preferably in the form of relatively thin flat strips or tapes which extend around the pulley 52 in overlying or superposed relation to each other. It will be seen from Fig. 3 that the underlying tape 54a serves the lowermost bin and has its opposite ends connected to the yoke 55 corresponding with this bin. The second tape 54b serves the next higher

bin of the row and has its ends connected with the yoke corresponding with this bin. It will be seen that the succeeding tapes in the group or series serve the successive bins with the topmost tape 54a serving the uppermost bin of the row. The tapes 54 are maintained under predetermined tension by means of tension springs 57 located adjacent the yokes 55, so that when oscillating motion is imparted to the pulley 52 the tapes will be driven or shifted to cause reciprocating feeding and retracting strokes of the ejector shafts 28 and the ejectors 26 carried thereby.

To provide for a free movement of the tapes 54 and to prevent binding of the guide members 48 in the guideways 47, each guideway is provided with a pair of upper and lower idler pulleys 58 and 59. These idler pulleys are mounted on the side walls 13 adjacent the ends of the guideways 47 and each pair of pulleys serves to guide one of the tapes in a substantially straight line along its guideway. The lowermost bin of the group is preferably provided only with the upper idler pulley 58 although a lower idler pulley 59 can also be provided for this bin if desired. When the lower idler pulley 59 is omitted the oscillatable main pulley 52 is constructed in the form of a pulley sector so as to permit one end of the tape 54a to pass directly to the tension spring 57 and the yoke 55. As shown in Fig. 3, the lower idlers 59 are disposed in an arcuately extending row corresponding with the bottom 16 of the housing and serve to support and guide the group of superposed tapes.

Oscillating movement can be imparted to the main pulleys 52 by any suitable driving mechanism. In this instance the driving mechanism provided for this purpose is mounted on the base 11 beneath the curved or sloping bottom wall 16 of the housing 10 and comprises an electric motor 61 which is connected with a reduction gear 62 by means of the belt 63. Cranks 64 carried by a rotating crankshaft 65 have crankpins 66 which are connected with crankpins 67 of the main pulleys 52 by means of the links 68. Rotation of the crankshaft 65 causes pushing and pulling forces to be transmitted through the links 68 for producing a substantially 90° oscillating movement of the main pulleys 52. The operation of the motor 61 is controlled by means of a suitable switch 69 which is adapted to be actuated by a pedal 70 located at a convenient point adjacent the front of the housing 10. When the pedal 70 is depressed the switch 69 is closed to thereby energize the motor and cause a feeding stroke of the ejectors 26. When the pedal is released a tension spring 71 returns the same to its initial position thereby opening the switch 69 and deenergizing the motor 61.

Reverting now to the paper guide or hood 22, it will be seen from the drawings that this member is a funnel-like structure having a plurality of outwardly converging partitions or guide plates 72 therein. The guide plates 72 form extensions of the partition walls 17 and define outwardly converging guide passages 73 which register with the open ends of the bins 18 and connect such open ends of the bins with the delivery opening or slot 23.

During the operation of this improved collating apparatus, the feeding of the sheets from the bins 18 by the outward strokes of the ejectors 26 in the manner above described, causes the sheets to be pushed outwardly through the guide passages 73 of the hood 22. Because of the con-

verging relation of these guide passages the sheets are brought into a relatively compact group or bundle 24 as they emerge from the hood through the delivery opening 23. The bundle 24 can be conveniently grasped by the operator at the proper time and withdrawn from the hood 22.

To enable the operator to obtain a firm grasp on the bundle 24, the outer shell and the partition walls 72 of the hood 22 are arcuately notched or recessed as indicated at 75 which will permit the operator's hand, or a portion thereof, to be extended partway into the hood. The hood 22 is also provided with a hinge or pivotal connection 76 which will permit the same to be swung from the closed position shown in Fig. 3 to an open position affording access to the bins 18 and the ejectors 26.

As shown in Figs. 1 and 2, the housing 10 may be provided with outer side walls or covers 77 which are located adjacent the side walls 13 and are suitably attached to the housing. The covers 77 conceal and protect the actuating mechanism for the ejectors 26 so as to prevent damage to this apparatus or personal injury from accidental contact therewith. These covers also improve the appearance of the apparatus.

Figs. 10 and 11 show a modified construction for the ejectors which feed the sheets from the bins. In this modified construction the ejector 80 carries a friction roller 81 which is similar to the rollers 87 of Fig. 4 and is shiftable in slots 82 in a similar manner. A yoke 83 carried by the ejector has a substantially U-shaped brake element 83a adapted to be engaged by the roller for holding the latter against rotation during the feeding stroke of the ejector. The yoke 83 is mounted on the ejector 80 by means of the lugs 83b and 83c which engage in the slots 84 and 85 of the ejector. This yoke has an effective position in which it is shown in Figs. 10 and 11 but when it is desirable to have the roller 81 turn freely for both feeding and return strokes of the ejector, as for example, when the bin is empty, the yoke is shifted to engage the lugs 83b in the slots 86 at which time the brake element 83a will not be engaged by the roller 81.

From the foregoing description and the accompanying drawings it will now be readily understood that the present invention provides an improved and simplified collating apparatus by which individual sheets can be simultaneously fed at a relatively rapid rate from a plurality of bundles and collected in a desired order or sequence. It will be seen also that the novel construction for the ejectors and the ejector actuating mechanism insures a smooth and positive actuation so that sheets will be properly fed from all of the bundles without skipping or missing. It will be seen also that the novel paper guide or hood above described facilitates the work of the operator in removing the bundle or group of collected sheets from the apparatus.

Although the improved collating apparatus has been illustrated and described in considerable detail, it will be understood, of course, that the invention is not intended to be correspondingly limited in scope but should be regarded as including all changes and modifications coming within the spirit of the invention and the scope of the appended claims.

Having thus described my invention, I claim:

1. A collator comprising a housing having a plurality of bins adapted to contain bundles of sheets, ejectors movable in said bins for delivering individual sheets therefrom including members ex-

tending transversely of said bins and adapted for translatory movement therein, an oscillatable pulley, means for oscillating said pulley, and flexible tapes extending around said pulley in superposed relation to be driven thereby, each tape having its ends connected with one of said members.

2. A collator comprising a housing having side walls and partitions defining a plurality of bins adapted to contain bundles of sheets, said side walls having paired slots therein communicating with said bins, shafts extending through said bins and slots, ejectors carried by said shafts and disposed in said bins for cooperation with said bundles, said shafts being shiftable in said bins in the direction of said slots for actuating said ejectors, a pair of members oscillatable about a common axis, means for driving said oscillatable members, and elongated flexible members connecting said shafts with said oscillatable members to be shifted by the latter.

3. A collator comprising a housing having side walls and partitions defining a plurality of bins adapted to contain bundles of sheets, said side walls having paired slots therein communicating with said bins, ejectors reciprocable in said bins for delivering individual sheets therefrom and having means projecting through said slots, idler pulleys adjacent the ends of said slots, a pair of pulleys oscillatable about a common axis, means for driving said oscillatable pulleys, and flexible tapes extending over said idler pulleys and in superposed relation around said oscillatable pulleys and having their ends connected with the projecting means of said ejectors.

4. A collator comprising a housing having side walls and partitions defining a plurality of bins adapted to contain bundles of sheets, said side walls having paired slots therein communicating with said bins, guideways on said walls substantially coextensive with said slots, ejectors reciprocable in said bins for delivering individual sheets therefrom including means projecting through said slots and guide members operable in said guideways, idler pulleys adjacent the ends of said guideways, a pair of pulleys oscillatable about a common axis, means for driving said oscillatable pulleys, and flexible tapes extending over said idler pulleys and in superposed relation around said oscillatable pulleys and having their ends connected with the projecting means of said ejectors.

5. A collator comprising a housing having therein a plurality of bins adapted to hold bundles of sheets with the planes of the sheets of the several bundles passing substantially through a common axis, means operable to deliver individual sheets from said bins, and a hood having a delivery opening and outwardly converging passages extending between said bins and said delivery opening.

6. A collator comprising a housing having therein a plurality of bins adapted to hold bundles of sheets with the planes of the sheets of the several bundles passing substantially through a com-

mon axis, means operable to deliver individual sheets from said bins, and a hood having a delivery opening and outwardly converging passages extending between said bins and said delivery opening, said hood being hinged to said housing for swinging to an open position to permit the insertion of said bundles into said bins.

7. In apparatus of the character described and having a bin adapted to contain a bundle of sheets, an ejector reciprocable in said bin for feeding individual sheets therefrom, said ejector having a friction roller engageable with said bundle and a locking means adjacent the roller, said roller being shiftable from a free-rolling position to a position in engagement with said locking means in which the latter holds the roller against rotation.

8. In apparatus of the character described and having a bin adapted to contain a bundle of sheets, an ejector reciprocable in said bin for feeding individual sheets therefrom and comprising a bracket having diverging portions provided with locking elements, and a substantially U-shaped member pivoted on said bracket and having forwardly extending spaced arms provided with friction means engageable with said bundle, said U-shaped member being adapted to be swung to a non-feeding position in which said friction means is disengaged from said bundle and said arms are releasably engaged with said locking elements.

9. An apparatus of the character described and having a bin adapted to contain a bundle of sheets, an ejector reciprocable in said bin and normally in position to feed individual sheets therefrom and comprising a bracket, a member pivoted on said bracket and having friction means engageable with said bundle, said member and bracket having other portions adapted to be brought into interlocking relationship and said member being adapted to be swung to a non-feeding position in which position said portions of member and bracket are in engagement and said friction means is disengaged from said bundle, and means for releasably holding said interlocking portions of said member and said bracket in interlocking relationship.
